UNITED STATES PATENT OFFICE.

WILLIAM F. HUDSON, OF PHILADELPHIA, PENNSYLVANIA.

DESIGN FOR A CRANK-CASE-REPAIR ARM.

57,047.

Specification for Design.

Patented Feb. 1, 1921.

Application filed November 22, 1919. Serial No. 339,961. Term of patent 14 years.

To all whom it may concern:

Be it known that I, WILLIAM F. HUDSON, a citizen of the United States, residing at Philadelphia, in the county of Philadelphia and State of Pennsylvania, have invented a new, original, and ornamental Design for Crank-Case-Repair Arms, of which the following is a specification, reference being had to the accompanying drawing, forming part thereof.

The figure is a perspective view of a crank case repair arm, showing my new design.

I claim:

The ornamental design for a crank case repair arm, as shown.

WILLIAM F. HUDSON.
